UNITED STATES PATENT OFFICE.

AUGUST LANG, OF PITTSBURG, PENNSYLVANIA, ASSIGNOR TO GEORGE DUNCAN & SONS, OF SAME PLACE.

DESIGN FOR A GLASS VESSEL.

SPECIFICATION forming part of Design No. 16,760, dated June 29, 1886.

Application filed April 28, 1886. Serial No. 200,485. Term of patent 7 years.

To all whom it may concern:

Be it known that I, AUGUST LANG, of the city of Pittsburg, in the county of Allegheny and State of Pennsylvania, have, by my own 5 industry, genius, efforts, and expense, invented and produced a new and original impression, ornament, or pattern to be placed on or worked into an article of manufacture—viz., a Glass Vessel; and I do declare the following to be a 10 full, clear, and exact description thereof, reference being had to the accompanying drawing, which is a perspective side view of a glass vessel embodying my design.

In the drawing, 2 represents a pattern in relief 15 on the sides of a glass vessel, consisting of a series of adjacent geometrical figures. This pattern is divided at intervals by a number of vertical smooth stripes, 3, which extend from end to

end of it. The pattern 2 and stripes 3 are differently colored, so as to show a contrast, 20 which is the distinguishing feature of the design, and presents a beautiful appearance.

I claim—

The design for glass vessels herein shown and described, the same consisting in a glass 25 vessel whose sides are provided with a raised pattern and a number of stripes intersecting the said pattern, the said stripes being differently colored relatively to the raised pattern.

In testimony whereof I have hereunto set 30 my hand.

AUGUST LANG.
